UNITED STATES PATENT OFFICE.

FREDERIC H. PARKHURST, OF BANGOR, MAINE, ASSIGNOR TO THE J. F. PARKHURST & SON CO., OF BANGOR, MAINE, A CORPORATION OF MAINE.

WARDROBE-TRUNK.

No. 822,384.

Specification of Letters Patent.

Patented June 5, 1906.

Application filed October 12, 1905. Serial No. 282,371.

To all whom it may concern:

Be it known that I, FREDERIC H. PARKHURST, a citizen of the United States, residing at Bangor, county of Penobscot, and 5 State of Maine, have invented an Improvement in Wardrobe-Trunks, of which the following description, in connection with the accompanying drawings, is a specification, like numerals on the drawings representing 10 like parts.

This invention relates to that class of wardrobe-trunks which are constructed with a hanging-compartment in which garments may be hung and with a closet-compartment 15 which may contain drawers or which may be made with shelves that are closed by doors; and the invention has for its object to provide a novel means for locking in closed position either the drawers or the doors of the 20 closet-compartment when the trunk is closed.

In the drawings, Figure 1 is a perspective view showing a wardrobe-trunk embodying my invention, and Fig. 2 is a horizontal section showing the manner in which the drawers 25 and doors of the closet-compartment are locked when the trunk is closed.

The trunk illustrated has the two parts 3 and 4, the part 3 constituting a hanging-compartment having an open front, and the part 30 4 constituting a closet-compartment in which drawers 5 are received and which may also have one or more hinged doors or flaps 50 to close shelves or other small compartments.

When the trunk is closed, the front of each 35 drawer, as well as the closed door 50, is adjacent the open front of the hanging-compartment. When these trunks are in use, the hanging-compartment is not always full of clothes, and consequently when the trunk is 40 closed there is apt to be more or less space between the front of the drawers 5 and doors 50, and the device 8 is employed to retain the clothes in place, and unless some means is employed for holding the drawers and 45 doors closed they are likely to be thrown open during the transportation of the trunk.

In accordance with my improvement I lock the drawers and doors in place by means of one or more locking-strips 6, which are 50 rigidly secured to one or both edges 7 of the

hanging-compartment, the locking strip or strips being of a shape to overlie one or both edges of the front of each of the drawers 5 or doors 50 when the trunk is closed. In the drawings I have shown one locking-strip 55 5. This locking-strip 6 is not of a width to interfere in any way with the placing of garments in or removing them from the hanging-compartment 3, but is merely wide enough to lap over the front edge of the 60 drawers and doors when the trunk is closed, and thus lock the drawers and doors firmly in place.

The clothes-retainer 8 may be of any suitable construction, and the locking-strip 6 65 will be of such a length and so placed that it does not in any way interfere with the operation of the clothes-retainer 8. In the form of the invention herein shown this clothes-retainer is in the form of a gate, which is 70 hinged to blocks slidably mounted in guides 9 on the side of the compartment 3, as shown in my Patent No. 768,683, dated August 13, 1904. Where this form of clothes-retainer is employed, the strip 6 will be situated between the two guides 9 and will be so placed 75 as not to interfere with the free sliding movement of the clothes-retainer or its swinging movement about its hinges 10. By making the strip a comparatively narrow one it does not appreciably reduce the size of the open end of the wardrobe-compartment, nor does it interfere in any way with the placing of clothes therein or their removal therefrom.

In some trunks the closet-compartment 85 may be filled entirely with drawers and in other trunks it may have only shelves and small compartments that are closed by doors. In either case, however, the locking-strip operates in the same way to hold the drawers or 90 doors closed when the trunk is closed.

Having fully described my invention, what I claim as new, and desire to secure by Letters Patent, is—

A wardrobe-trunk comprising two parts 95 hinged together, one part constituting a hanging-compartment having an open front, and the other part constituting a closet-compartment, said latter compartment being subdivided into smaller compartments, closing 100

means for the various compartments, and a locking-strip secured to the front edge of the hanging-compartment and adapted to overlie the closing means when the trunk is closed, and thereby lock said means in closed position.

5 In testimony whereof I have signed my

name to this specification in the presence of two subscribing witnesses.

FREDERIC H. PARKHURST.
